Primary Examiner — Jennifer Rivard

(57) CLAIM

The ornamental design for a nail lamp, as shown and described.

DESCRIPTION

FIG. 1 is a front elevational view of a nail lamp showing my new design;

FIG. 2 is a rear elevational view thereof;

FIG. 3 is a left side elevational view thereof;

FIG. 4 is a right side elevational view thereof;

FIG. 5 is a top plan view thereof; and,

FIG. 6 is a bottom plan view thereof.

The broken lines shown in drawings are for the purpose of illustrating portions of the nail lamp and form no part of the claimed design.
